UNITED STATES PATENT OFFICE.

MEREDITH G. STANLEY, OF CINCINNATI, OHIO.

BANK.

1,036,366.

Specification of Letters Patent. Patented Aug. 20, 1912.

Application filed April 30, 1912. Serial No. 694,217.

To all whom it may concern:

Be it known that I, MEREDITH G. STANLEY, citizen of the United States, residing at Cincinnati, in the county of Hamilton and State of Ohio, have invented certain new and useful Improvements in Banks, of which the following is a specification, reference being had therein to the accompanying drawing.

10 This invention relates to portable banks such as are used for the accumulation of coins, and has special reference to a bank provided with novel means for preventing coins from being removed from the bank 15 after being placed therein.

The principal object of the invention is to provide an improved form of coin chute for use in connection with a bank of this description.

20 With the above and other objects in view, this invention consists in general of certain novel constructions, combinations and arrangements of parts, as will be hereinafter fully described, illustrated in the accompanying drawings, and specifically claimed.

25 In the accompanying drawings, like characters of reference indicate like parts in the several views, and Figure 1 is a side elevation of a bank constructed in accordance 30 with this invention. Fig. 2 is a section on the line 2—2, Fig. 1. Fig. 3 is a section on the line 3—3, Fig. 2. Fig. 4 is a section on the line 4—4, Fig. 2. Fig. 5 is a view showing a certain valve used in connection 35 with this bank. Fig. 6 shows a modified form of coin chute. Fig. 7 shows a second modification of the coin chute. Fig. 8 is a section on the line 8—8, Fig. 7.

40 In the preferred form, as illustrated in Figs. 1 to 5, the invention consists in a casing 10 made of any suitable metal such as sheet tin or the like and this casing may be plain or ornamental as desired. The casing is closed at its upper end permanently 45 by a top 11 soldered or otherwise secured thereto. The lower end of the casing is likewise provided with a closure 12 and in the form herein illustrated this closure is held upon the casing by means of a frangible 50 strap 13 which, in the present instance has been indicated as a band of paper or the like. On this paper band is imprinted a promise as to the date of opening of the bank it being 55 the intention to employ these banks in connection with a collection of subscriptions for churches or society dues or contribu-

tions. Of course, it will be obvious that any other suitable closure may be used. In the upper part of the casing 10 there is provided a slot 14 for the introduction of a 60 coin, and leading from this slot 14 is a chute 15 which extends transversely across the casing and is open at its other end at one side as indicated at 16. This chute communicates with a chute 17 which leads 65 from this opening and extends backward along the side of the chute 15 and terminates against the wall of the casing wherein the slot 14 is formed, the chute however being displaced with reference to this slot. 70 The chute 17 is provided with an open bottom 18 at the end adjacent the opening 14. In the formation of the two chutes there is preferably employed a single strip of 75 sheet metal properly stamped and cut to provide the opening and this strip of metal is bent in the manner illustrated in Figs. 3 and 4. In the chute 17 there is provided a valve which consists of a plate 19 having one end pivoted as at 20 and provided with a limit stop 21 to prevent too great movement of the valve when closing the chute. In the operation of this form of the device the coin is dropped in the opening 14 and the bank tilted until the coin 85 runs down the chute 15 to the opening 16. The bank is then tilted at right angles to the previous movement whereupon the coin will fall into the chute 17 and upon further tilting of the bank the coin will pass down 90 this chute and drop through the opening 18.

It is preferred that the chutes 15 and 16 be positioned centrally or nearly centrally of the width of the casing 10 so that the casing cannot be used as a guide to slide 95 the coin from within the bank into the opening 18 and thus into the chute 17. Consequently the only way a coin can be brought into the opening 18 after once being deposited in the bank is to invert the casing and 100 shake the same up and down until the coin happens to get in position edgewise to the opening 18 and in alinement therewith. However, even this will not permit the passage of the coin outward along the chute 105 17 since the inverting of the bank will cause the valve 19 to assume the position shown in dotted lines in Fig. 5, thus closing off the chute 17 from the opening 16. It is thus impossible to remove a coin once it has been 110 placed within the bank unless the bottom closure be removed.

In the form shown in Figs. 6 and 7 the casing 10 is provided with a horizontally disposed opening 22 which communicates with a chute 23 opening laterally at the end 5 remote from the opening and leading into a chute 24 provided with an open end and having at the open end a tongue 25 as in Fig. 6, or a plurality of tongues 26 as in Fig. 7. These tongues are spring metal and 10 are so bent that they normally engage the top of the casing 10. In this form the coin slipped through the opening 22 will slide through the chute 23, then drop into the chute 24, and pass out of the open end of 15 that chute, lifting the tongue or tongues as it passes out. Now these tongues act as closures for the mouth of the chute so that it is impossible to replace a coin inside the chute after it has once been deposited in 20 the bank.

It is to be noted that in all of the forms shown the chute is entirely held within the casing so that no indication is given of the interior construction of the device by the 25 appearance of the exterior. Furthermore it will be noted that in each instance the chutes communicate with each other by lateral openings so that the movement necessary to deposit the coin involves tilting the device in three directions, that is to say, first 30 depressing the end of what may be termed the primary chute, then tilting the chutes laterally, and then depressing the terminal end of what may be termed the secondary chute.

There has thus been provided a simple and efficient device of the kind described, and for the purpose specified.

It is obvious that many minor changes 40 may be made in the form and construction of this device without departing from the material principles thereof, and it is therefore not wished to confine the invention to the exact form herein shown and described, 45 but it is wished to include all such as properly come within the scope claimed.

Having thus described the invention what is claimed as new, is:—

1. In a bank of the kind described, a casing 50 having an inlet slot therein, a chute within the casing leading from the inlet slot and extending across the casing, and a second chute extending parallel to the

first chute and communicating therewith by a lateral opening, said chutes lying in 55 spaced relation to the lateral sides of the casing whereby coins lying on the side of the casing will be spaced from said chutes.

2. In a bank of the kind described, a casing having an inlet slot therein, a chute 60 within the casing leading from the inlet slot and extending across the casing, a second chute extending parallel to the first chute and communicating therewith by a lateral opening, and means to prevent the 65 replacement of the coin in the chute, said chutes lying in spaced relation to the lateral sides of the casing whereby coins lying on the side of the casing will be spaced from 70 said chutes.

3. In a bank of the kind described, a casing having a vertically disposed coin inlet in one side wall, a chute having its longest cross section vertical extending across the casing from the inlet, and a second chute 75 lying side by side with the first mentioned chute and communicating therewith by a lateral opening at the end remote from the inlet, said second chute having an opening in its bottom to permit the coin passing out 80 of the chute, said chutes lying in spaced relation to the lateral sides of the casing whereby coins lying on the side of the casing will be spaced from 85 said chutes.

4. In a bank of the kind described, a casing having a vertically disposed coin inlet in one side wall, a chute having its longest cross section vertical extending across the casing from the inlet, and a second chute 90 lying side by side with the first mentioned chute and communicating therewith by a lateral opening at the end remote from the inlet, said second chute having an opening in its bottom to permit the coin passing out 95 of the chute, said second chute being provided with stop means to prevent the return of coins therethrough, said chutes lying in spaced relation to the lateral sides of the casing whereby coins lying on the side of the casing will be spaced from 100 said chutes.

In testimony whereof I hereunto affix my signature in presence of two witnesses.

MEREDITH G. STANDLEY.
